UNITED STATES PATENT OFFICE

LEWIS J. BAZZONI, OF SWAMPSOFT, MASSACHUSETTS, ASSIGNOR TO UNITED SHOE MACHINERY CORPORATION, OF PATERSON, NEW JERSEY, A CORPORATION OF NEW JERSEY

BURNISHING MACHINE

Application filed January 29, 1929. Serial No. 335,772.

This invention relates to burnishing machines and is illustrated as embodied in a machine for burnishing or setting the edges of top lifts such, for example, as those employed on Louis heels.

Owing to the small radius of curvature of portions of a top lift for a Louis heel, and the proximity of the top lift to the cover of the heel, the peripheral surfaces of the top lift may be set on an ordinary edge setting machine having a rapidly oscillating tool only with considerable difficulty. In holding a lift having a small radius of curvature against a reciprocating edge setting tool, the operator must be extremely careful that the tool does not accidentally slide over an abruptly curved portion and mar the cover for the heel by a rapid succession of blows imparted sidewise of the heel before he can 10 gain proper control of the work. Moreover, the convex work-engaging surface of a tool commonly used in a machine employing an oscillating tool may burnish the edge of a top lift of small radius of curvature unevenly, on account of the small area of contact 15 between the tool and top lift, leaving a series of flattened portions.

Therefore, an object of the invention is to provide improved apparatus for burnishing 20 heels, or top lifts thereof, which obviates the above difficulties in the presentation of the work to the operating tools but which is attended with the well-known advantages of a rapidly oscillating tool arising from its to 25 and fro movement. In accordance with this object of the invention the illustrated machine comprises a rotating tool having a concave burnishing surface to facilitate the presentation of the work thereto and which tool is constructed and arranged alternately to 30 burnish the work in opposite directions.

To this end the concave burnishing element is provided with a plurality of burnishing rolls, which it partially encases, and which 35 are driven upon the rotation of the concave burnishing element, the rolls being arranged so as momentarily to supplant the burnishing action of the concave burnishing surface by a burnishing action in the opposite direction. 40 Hence, as the tool is rotated in contact with a

piece of work, it is burnished alternately in opposite directions, although the burnishing elements of the illustrated machine rotate about their respective axes in the same angular direction. The radius of curvature of 55 the concave burnishing surface is substantially equal to the greatest curvature of heels commonly operated upon. By thus providing a burnishing tool the work engaging surface of which is contoured similarly to the heel to be operated upon, the extent of contact between the tool and the work is increased, thereby insuring a more smoothly 60 burnished peripheral surface on the lift or heel to be operated upon. Furthermore, as 65 the operator holds the work against such a concave surface it tends to remain in contact therewith at its highest point.

When a machine having a reciprocating burnishing tool is used to set the edges of 70 soles of shoes, the operator may err in presenting the sole edge to the tool by substantially the width of the crease between the upper and the sole without injuring the upper. On the other hand, the peripheral 75 surface of a top lift attached to a wood heel having a cover is finished so that it is substantially continuous with the outer surface of the cover, or with the remaining lifts of the heel if it is made entirely of leather. 80 Hence, a slight error on the part of the operator in presenting the top lift to the edge setting tool might easily result in marring the adjacent surface. To obviate the above difficulty, and in accordance with another 85 feature of the invention, the illustrated burnishing tool has been provided with means adjustably fixed thereto and constructed and arranged to align the attaching surface of a top lift with the end face of the 90 tool as the top lift is held against said means. To this end, in the illustrated embodiment of the invention, this means comprises a gage in threaded engagement with the tool, which 95 gage may be adjusted so as to vary the width of the burnishing surface of the tool in accordance with the thickness of the top lift to be treated.

These and other objects and features of the invention will be best understood from the 100

following description when read in connection with the accompanying drawings, in which

Fig. 1 is a side elevation of a burnishing machine embodying my novel burnishing tool;

Fig. 2 is an end elevation showing only the tool;

Fig. 3 is a sectional elevation, taken along the line III—III of Fig. 2, showing part of the machine frame;

Fig. 4 is a sectional elevation taken along the line IV—IV of Fig. 3; and

Fig. 5 is a fragmentary section showing a heel held against the tool in operative position.

A tool arbor 6 (Fig. 3) is journaled in a frame 8 and carries a tool body 10 which is held on a tapered end 12 of the arbor by a screw 14 and associated bushings 16 one of which is slit, as shown in Fig. 2, to provide a tight wedge fit between the tool body 10 and the tapered end 12 of the tool arbor 6 as the screw 14 is made up. As the tool arbor 6 is rotated, burnishing rolls 18 rigidly connected to the outer ends of spindles 20 journaled in bearings 22 in the tool body 10 are rotated bodily therewith. The rolls 18 also rotate about their own axes, which rotation is derived from their bodily rotation by virtue of the geared connection of the spindles 20 to the frame of the machine through pinions 24 which are carried by the spindles 22 and which run in mesh with a ring gear 26 secured to the frame by three screws 28. Provision is made in shaping the rolls 18 for preventing oil, escaping from the bearings 22 in which the spindles 20 are journaled, from running to the work-engaging surfaces of the rolls. This end is attained, in the illustrated embodiment of the invention, through the use of a peripheral groove 30 (Fig. 3) in the intermediate portion of the rolls. It is apparent that any oil flowing toward a burnishing roll along a spindle 20 will not flow past the peripheral groove 30 but will accumulate at the periphery of the left-hand face of the roll and be thrown therefrom by the effect of centrifugal force created by the rotation of the roll.

A ring-shaped burnishing member 32 having a concave inner burnishing surface 34 is fixed by screws 36 (Figs. 1 and 2) to two laterally extending diametrically opposed lugs 38 which are integral with the burnishing tool body 10. The end surface of the last-mentioned burnishing member 32 is in alinement with the outer end faces of the burnishing rolls 18, and the peripheries of these rolls are substantially tangent (Fig. 2) to the concave work-engaging surface 34 of the burnishing member 32. A guide 40 is in threaded engagement with the burnishing tool body 10, as indicated at 42, and may be held in any desired position of axial adjust-

ment by means of lock screws 44 threaded into the guide 40 and bearing against the tool body 10. The annular end face 46 of the guide member, as shown in Fig. 5, may be accurately adjusted with respect to the end faces 48 of the burnishing members, so that the attaching face 50 of the top lift 52 may be alined therewith for the purpose hereinbefore set forth. A housing 54 surrounds that part of the tool body in which the rotating spindles and pinions are mounted, preventing the entry of dirt in the vicinity of the working parts and the egress of oil which might otherwise be thrown from the rapidly rotating parts.

It is to be noted from Fig. 3 that the diameter of the work-engaging portions of the burnishing rolls 18 is substantially greater than the pitch diameter of the pinions which drive them. As the tool body 10 is rotated by the arbor 6, the burnishing rolls 18 are also rotated in the tool body about their own axes, owing to their connection to the ring gear 26 through the pinions 24 which run in mesh about the gear 26 as the tool rotates. If the rolls 18 were made equal in diameter to the pitch diameter of the pinions 24, they would merely roll about a piece of work presented thereto just as the pinions rotate about the ring gear 26. However, since the rolls are of substantially greater diameter than that of the pinions which drive them, their peripheral speed is proportionately greater than that of the pinions; but since the peripheral motion of the rolls 18 at the point of engagement with the work is in a direction opposite to that of the concave burnishing surface 34 with respect to a stationary piece of work, the burnishing action of the rolls 18 will be in a direction opposite to that of the concave burnishing element 32. Thus, the burnishing action of the burnishing member 32 is supplanted by the opposite burnishing action, as indicated by the arrows in Fig. 2, of the burnishing rolls 18 as the burnishing tool rotates past a piece of work held thereagainst. The tool arbor 6, and hence the tool body 10, may be driven from any suitable source of power by means of a belt 56 engaging the pulley 58 fixed to the arbor 6.

In the operation of the machine the gage 40 is first adjusted so that when the tread surface of a top lift of a heel to be operated upon is held thereagainst the attaching surface is in alinement with the end surfaces 48 of the burnishing elements, as indicated in Fig. 5. Such an adjustment precludes the possibility of the covering for a wood heel, or the lifts in a corresponding position in a leather heel, being marred or damaged by the burnishing elements. After power has been applied to the machine and the burnishing tool rotated, the periphery of the lift, except the breast portion, may be set by holding

it against the burnishing surface of the tool in such a manner as that illustrated in Fig. 5. The lift face to be burnished may thus be completely operated upon either by rotating the shoe about an axis perpendicular to the tread face of the lift or by bodily moving the shoe so that the lift moves in a path defined by the burnishing surface of the concave burnishing element 32 from one side of the axis of the tool to the other, as indicated in Fig. 2, by successive positions of a lift of a shoe being manipulated in this manner.

The invention, as illustrated herein, is particularly adapted for setting the edges of top lifts of relatively small heels such as Louis heels, but it is to be understood that top lifts of any size, and in fact the entire peripheral faces of heels, may be burnished in a machine embodying the invention, in which machine the operating tools, the work engaging faces of which are surfaces of revolution having like elements, are formed according to the shape and size of the surface to be burnished.

Having thus described my invention, what I claim as new and desire to secure by Letters Patent of the United States is:

1. In a heel burnishing machine, a rotating burnishing tool comprising concave and convex work-engaging elements having the same direction of rotation but constructed and arranged to burnish a piece of work alternately in opposite directions.

2. In a heel burnishing machine, a burnishing tool comprising rotating work-engaging elements and connections between said elements whereby one of said elements is driven by another thereof, said elements and connections being constructed and arranged to have the same angular direction of rotation about their respective axes but to burnish a piece of work alternately in opposite directions.

3. In a heel burnishing machine, a burnishing tool comprising rotating work-engaging elements one of which partially encloses the others, said elements being constructed and arranged to burnish a piece of work alternately in opposite directions.

4. In a heel burnishing machine, a rotating burnishing tool comprising work-engaging elements one of which partially encloses the others, connections between said elements whereby the rotation of the enclosing element drives the others, said elements being so arranged and said connections so constructed that a piece of work held against said elements is burnished alternately in opposite directions as the tool is rotated, and means for rotating the tool.

5. In a heel burnishing machine, a burnishing tool comprising rotating work-engaging elements one of which partially encloses the others, and connections between said elements whereby the rotation of the enclosing element drives the others in the same direc-

tion of rotation, said connections and elements being so constructed and arranged that a piece of work held against the tool is burnished alternately in opposite directions.

6. In a heel burnishing machine, a burnishing tool having a concave work-engaging element for facilitating the presentation of the work to the tool, a convex element carried by said concave element, connections between said elements whereby the convex element is driven by the rotation of the concave element, said work-engaging elements being arranged alternately to operate on the work held thereagainst as the tool is rotated, and means for rotating the tool.

7. In a heel burnishing machine, a burnishing tool having a rotatable concave work-engaging element for facilitating the presentation of the work to the tool, a convex element carried by said concave element, connections between said elements whereby the convex element is driven by the rotation of the concave element in the same direction, said work-engaging elements and connections being constructed and arranged to burnish the work held against the tool alternately in opposite directions as the tool is rotated, and means for rotating the tool.

8. In a heel burnishing machine, a burnishing tool having a rotatable concave work-engaging element, a convex burnishing element carried by said concave element arranged to supplant momentarily the burnishing action of the concave element as it is rotated by a burnishing action in the opposite direction, and means for rotating the tool.

9. In a heel burnishing machine, a burnishing tool comprising a rotatable burnishing member carrying a rotating burnishing roll, the work-engaging surfaces of both being circular and substantially tangent to each other.

10. In a heel burnishing machine, a burnishing tool comprising a rotatable burnishing member carrying a rotating burnishing roll, the work-engaging face of the latter being substantially tangent to that of the former.

11. In a heel burnishing machine, a burnishing tool comprising a rotatable burnishing member carrying a burnishing roll the work-engaging surfaces of which burnishing elements are cylindrical and tangent.

12. In a heel burnishing machine, a burnishing tool comprising a rotatable burnishing member carrying burnishing rolls rotating therein and with respect thereto, the work-engaging surfaces of the rolls being substantially tangent to that of said rotatable burnishing member.

13. In a heel burnishing machine, a rotatable burnishing tool, and a burnishing roll rotatably mounted in said tool, the work engaging surfaces of said tool and said roll being surfaces of revolution.

14. In a heel burnishing machine, a ro-

- tatable burnishing tool, and a plurality of burnishing rolls rotatably mounted in said tool, the work engaging surfaces of said tool and said rolls being surfaces of revolution having like elements.
15. In a heel burnishing machine, a rotatable burnishing tool, a plurality of burnishing rolls rotatably mounted in said tool, the work engaging surfaces of said tool and said rolls being surfaces of revolution having like elements, connections between said tool and rolls causing a rotation of the latter when the tool is rotated, and means for rotating the tool.
16. In a heel burnishing machine, a burnishing tool having a concave work engaging surface, and a burnishing roll mounted in said burnishing tool, the work engaging surfaces of said burnishing tool and roll being surfaces of revolution having like elements.
17. In a heel burnishing machine, a burnishing tool having a concave work engaging surface, a plurality of burnishing rolls mounted in said burnishing tool, the work engaging surfaces of said burnishing tool and rolls being surfaces of revolution having like elements, means for rotating said rolls operated by rotation of the tool, and means for rotating the tool.
18. In a heel burnishing machine, a burnishing tool having a concave work engaging surface, a plurality of burnishing rolls rotatably mounted in said burnishing tool, the work engaging surfaces of said burnishing tool and rolls being surfaces of revolution having like elements, geared connections between the rolls and the tool for causing the rolls to be rotated when the burnishing tool is rotated, and means for rotating the tool.
19. In a heel burnishing machine, a burnishing tool comprising a rotatable concave element and a convex element carried by said concave element, the work engaging faces of said elements being surfaces of revolution having like elements and being substantially tangent.
20. In a machine for burnishing top lifts of heels, in combination, a burnishing tool, means in threaded engagement therewith constructed and arranged to regulate the width of the work-engaging surface of the tool according to the thickness of the top lift to be burnished, and means for securing said last-mentioned means in adjusted position on the tool.
21. In a heel burnishing machine, in combination, a burnishing tool and means adjustably fixed thereto constructed and arranged to aline the attaching surface of a top lift with the end face of the tool as the lift is held against said means.
22. In a heel burnishing machine, in combination, an annular burnishing tool and means within said tool constructed and arranged adjustably to vary the width of the burnishing surface of the tool.
23. In a machine for burnishing the top lifts of Louis heels, a burnishing tool comprising a rotatable burnishing member having a concave work-engaging face the radius of curvature of which is substantially the same as the greatest radius of curvature of the periphery of the lift to be burnished, and rotating burnishing rolls partially incased in said burnishing member arranged momentarily to supplant the burnishing action of the burnishing member to the work by a burnishing action in a direction opposite to that of said burnishing member.
24. In a heel burnishing machine, a burnishing tool comprising a rotatable body, a burnishing member fixed in the body, burnishing rolls journaled in said body and partially enclosed by said burnishing member, means for imparting rotation to the rolls relative to said burnishing member as it is rotated, and a housing about said body enclosing said means.
25. In a heel burnishing machine, a burnishing tool comprising a rotatable body, a burnishing member having a concave work-engaging surface fixed to said body, a plurality of burnishing rolls journaled in the body and tangent to the work-engaging surface of the burnishing member, means for rotating the rolls operated by the rotation of the body, and means for rotating the body.
26. In a heel burnishing machine, means for burnishing a piece of work held thereagainst alternately in opposite directions comprising a rotating burnishing element having a concave work-engaging surface, a plurality of burnishing rolls the peripheral motion of which at the point of contact with the work is opposite to that of the concave burnishing element, means for driving said rolls by the rotation of said concave burnishing element, and means for rotating said concave burnishing element.
27. In a heel burnishing machine, a burnishing tool comprising a rotatable body, a burnishing member having a concave work-engaging surface fixed to said body, a plurality of burnishing rolls journaled in the body and substantially tangent to the work-engaging surface of the burnishing member, and connections between said rolls and said burnishing member constructed and arranged to drive the rolls upon rotation of the burnishing member at a greater peripheral velocity than that of the work-engaging surface of the concave burnishing member.
28. In a heel burnishing machine, a burnishing tool comprising a rotatable body, a burnishing member having a concave work-engaging surface fixed to said body, a plurality of burnishing rolls journaled in said body substantially tangent to the work-engaging surface of the burnishing member,

and connections between said rolls and said burnishing member constructed and arranged to drive the rolls in the same angular direction of rotation as that of the burnishing member but at a greater peripheral velocity.

5 29. In a heel burnishing machine, a burnishing tool comprising a rotatable body, a burnishing member fixed to said body, burnishing rolls journaled in said body arranged momentarily to supplant the burnishing action of the burnishing member as the tool is rotated, a gear, and pinions operatively associated with said rolls and meshing with 10 said gear for turning said rolls as the tool is rotated with respect to the gear.

15 30. In a heel burnishing machine, a burnishing tool comprising a rotatable body, a burnishing member having a concave working 20 surface fixed to said body, burnishing rolls journaled in said body and substantially tangent to said concave surface arranged momentarily to supplant the burnishing action of the burnishing member as 25 the tool is rotated, a gear, and pinions operatively associated with said rolls and meshing with said gear, said pinions having a pitch diameter less than the diameter of the rolls whereby the peripheral velocity of the 30 rolls exceeds the velocity of the concave burnishing surface.

In testimony whereof I have signed my name to this specification.

LEWIS J. BAZZONI.
